(57) **CLAIM**

The ornamental design for a spiral wing shaft for mixers, as shown and described.

DESCRIPTION

FIG. 1 is a front view of a spiral wing shaft for mixers showing our new design;
 FIG. 2 is a rear view thereof;
 FIG. 3 is a top plan view thereof;
 FIG. 4 is a bottom plan view thereof;
 FIG. 5 is a right side view thereof;
 FIG. 6 is a left side view thereof;
 FIG. 7 is a cross-sectional view taken along line 7—7 in FIG. 1; and,
 FIG. 8 is a cross-sectional view taken along line 8—8 in FIG. 1.
